UNITED STATES PATENT OFFICE.

PERCY M. ELLIOTT, OF CHICAGO, ILLINOIS.

SUPPORTING MECHANISM FOR FREIGHT-CAR DOORS.

1,099,919.

Specification of Letters Patent.

Patented June 16, 1914.

Application filed April 18, 1913. Serial No. 762,083.

To all whom it may concern:

Be it known that I, PERCY M. ELLIOTT, a citizen of the United States, residing at Chicago, in the county of Cook and State of Illinois, have invented certain new and useful Improvements in Supporting Mechanism for Freight-Car Doors, of which the following is a specification.

My invention relates in general to freight cars, and more particularly to means for supporting the doors and for closing the space between the upper edges of the doors and the overlying support.

In freight cars of the construction having sides composed of metal beams forming trusses outside of the wooden sheathing, it is necessary that the path of movement of the sliding doors should be spaced outwardly from the wooden sides a distance equal to the thickness of the metal beams in order that the doors may slide out of the plane of the trussed beams. This arrangement requires that the track from which the door is suspended should project outwardly from the car sides a considerable distance, and owing to the consequent exposed position of the top of the door it is necessary that a thoroughly weather and dust proof joint should be provided between the upper edge of the door and the car side.

Heretofore considerable difficulty has been experienced in providing tracks for supporting the sliding side doors of cars of the construction above referred to, which will prevent the ingress of water between the top of the door and the overlying beam forming the upper chord of a trussed car side. The weight of the door is such as to subject the track to strains which tend to separate it from the supporting flange of the longitudinal beam to which the track is secured and to thereby permit ingress of water. In my present invention I overcome this difficulty by so connecting the door track to the beam which supports the same as to at all times insure a weather-proof joint which will not be affected by the downward strain to which the track is subjected by the weight of the door.

My invention has for its object to provide means for supporting and guiding the door of a freight car of the type above referred to, which will not only securely support and properly guide the door in its opening and closing movements, but will also afford a

weather-proof joint between the top of the door and the top of the car door opening.

A further object of my invention is to provide means for supporting and guiding a sliding freight car door, and for forming a weather-proof joint between the door when closed and the door opening, which will be simple in construction, inexpensive to build, durable in use, and efficient in operation.

My invention will be more fully disclosed hereinafter with reference to the accompanying drawings, in which the same is illustrated as embodied in two convenient and practical forms, and in which—

Figure 1 is a side elevational view of a freight car door and the adjacent portions of the freight car embodying my invention; Fig. 2 an enlarged sectional view on line 2, 2, Fig. 1, and Figs. 3, 4 and 5, views similar to Fig. 2, showing modified forms of my invention.

Similar reference characters are used to designate similar parts in the several figures of the drawings.

Reference letter A designates a freight car, only so much thereof being shown as is necessary to fully illustrate my invention. The freight car to which my invention relates is of the type comprising metal beams forming side trusses within which the wooden sheathing is secured. As this type of freight car is well-known it is not necessary to describe the same in detail.

Reference characters B' and B² designate the upper ends of diagonal Z-beams forming parts of the trussed structure of the car side.

C designates the wooden sheathing located within the trussed metal beams and secured to them to form the inclosing side wall of the car.

D designates the longitudinal beam above the car side upon which the roof structure is supported.

Extending at each side of the car immediately below the roof and preferably secured to the longitudinal beam D by bolts e is a Z-beam forming the upper chord of the side truss. The web e' of the Z-beam E depends vertically and overlies the top plank of the wooden side C. The lower flange E' of the Z-beam projects outwardly across the plane of the diagonal Z-beams B' and B² and the other beams forming the side truss of the car.

It is necessary that a sliding door should have a path of movement outside of the longitudinal plane of the trussed beams of the side. Hence, it is necessary that the 5 track for the door to slide upon should project laterally beyond the lower horizontal flange E' of the Z -beam E . I, therefore, provide a horizontal plate F which is supported by the outwardly projecting horizontal flange E' of the Z -beam and is secured thereto by any suitable fastening 10 means, such for instance as rivets f . The plate F projects beyond the lower horizontal flange of the Z -beam and overlies the 15 plane of the door G so as to form a direct vertical support for the door.

In order to form an interlocking connection between the top of the door and the overlying supporting track consisting of the 20 plate F , a second horizontal plate F' is supported longitudinally beneath the plate F and is provided with a depending vertical flange f' located in a plane intermediate of the outer edges of the horizontal flange 25 E' of the supporting Z -beam E and the horizontal plate F . The second plate F' is preferably formed integrally with the plate F and is secured to the flange E' of the overlying supporting beam by the same 30 rivets f which support the plate F . The plates F and F' may be conveniently constructed by bending the sheet metal of which they are formed longitudinally, so that the plate F' will underlie the plate F , and by 35 further bending the outer portion of the underlying plate F' so as to form the depending flange f' .

In order to securely support the door and to insure freedom of sliding movement into 40 open and closed positions, a pair of hangers H' and H^2 are secured to the top of the door adjacent the front and rear edges thereof. Each of these hangers comprises a pair of anti-friction rollers K' and k , the former 45 of which overlies the outer edge of the plate F and directly supports the door thereon. The lower smaller guide roller k of each door hanger vertically underlies the outer portion of the plate F and should the 50 door be tilted longitudinally in applying force thereto for opening and closing it, such lower guide roller will engage beneath the track plate F and insure the free sliding of the door. It will be observed that the lower 55 guide roller k lies outside of the depending flange f' of the plate F' , while the upwardly projecting flange G' of the Z -beam along the top edge of the door lies within such downwardly projecting guide flange f' . It will, 60 therefore, be clear that the upper edge of the door is prevented from lateral movement either inwardly or outwardly.

In Fig. 3 I have shown a slight modification 65 of my invention, in which the underlying plate is formed separately from the

overlying plate. In this figure F^2 designates the first plate which underlies the supporting flange E' of the Z -beam E and projects outwardly beyond the same so as to vertically overlie the space occupied by the sliding door. F^3 designates the second plate which is provided with the depending guide flange f^3 along its outer edge. Both the plates F^2 and F^3 may be conveniently secured to the overlying supporting flange E' 75 by the same rivets f^2 .

In Fig. 4 I have shown another embodiment of my invention, in which the plate which forms the supporting track for the door overlies the flange of the Z -beam, while 80 the second plate on which is formed the depending guard flange underlies the supporting flange of the Z -beam. In this figure reference character F^4 indicates the plate which forms the supporting track of the 85 door, and reference character F^5 the plate on which is formed the depending guard flange f^5 . The same rivets f^4 may be used for passing through registering holes in the plates F^4 and F^5 and the interposed flange E' of 90 the supporting Z -bar, thereby serving as a common means for securing both plates to the Z -bar.

In Fig. 5 I have illustrated still another embodiment of my invention, in which reference character F^6 designates the upper plate which constitutes the track supporting the door hangers, while reference character F^7 designates the lower plate having formed on the outer edge thereof the depending guard flange f^7 . In this form of my invention the plate F^6 overlies the supporting flange E' of the Z -bar E and is rigidly secured thereto by the rivets f^6 , while the underlying plate F^7 only slightly overlaps the under surface of the supporting flange E' and is rigidly secured to the overlying plate F^6 by means of rivets f^8 . Washers F^8 surround the rivets f^8 and are interposed between the adjacent surfaces of the plates F^6 and F^7 so as to space the said plates apart a distance corresponding to the thickness of the supporting flange E' . In this form of my invention the plates F^6 and F^7 are connected together by the rivets f^8 and interposed washers F^8 prior to being secured to the car side, so that they may be simultaneously readily applied to the supporting flange E' by being driven laterally of the flange E' so that the outer edge of said flange will be forced between the plates—in the manner shown in Fig. 5—after which the rivets f^8 are secured in registering holes in the plate F^6 and underlying supporting flange E' . 115

In each of the several embodiments of my invention above described, it will be observed that a permanent weather-proof joint is provided between the door supporting track and the Z -bar which extends along 120 125 130 135

the car side above the door opening. In Fig. 2 the weight of the door tends to swing the outer edges of the track plates downwardly so that the inner edges of such plates are forced upwardly into tight contact with the under surface of the supporting flange E'. The water falling upon the upper surface of the supporting flange E' therefore cannot pass inwardly beneath such flange to the interior of the car, but flows along the upper surface of the plate F' and drips from the outer edge thereof outside of the door. The same action occurs in the form of my invention shown in Fig. 3, and the interior of the car is protected from ingress of water in the same manner.

In the form of my invention shown in Fig. 4 the underlying plate F⁵ serves to prevent any water which may leak between the overlying plate F⁴ and the supporting flange E', from passing beneath such flange to the interior of the car, inasmuch as the said plate F⁵ forms a permanent close contact with the underside of the supporting flange E', and any water which may pass between the plate F⁴ and the upper surface of such flange flows outwardly over the plate F⁵ and downwardly around the flange f⁵ thereof. Substantially the same action takes place in the form of my invention shown in Fig. 5 as that described in connection with Fig. 4. The washers F⁸ serve to form spaces between adjacent rivets f⁸ through which may flow any water which leaks between the plate F⁶ and the upper surface of the supporting flange E'. Any such water is prevented from flowing inwardly beneath the flange E' by reason of the close contact between the inner edge of the plate F⁸ and the under surface of the supporting flange E' of the Z-beam.

At the front edge of the door opening is provided a vertical bar M which forms a door post and projects beyond the truss beam at the car side into the plane of the door so as to form a stop to limit the closing movement of the door. The lower end of the vertical angle bar M overlies and is secured to the base channel beam N which forms the lower chord of the side truss. The upper end of the angle bar M is secured by a gusset plate O to the horizontal flange E' of the Z-beam E, as shown in Fig. 1.

R' and R² designate the usual guides for the lower edge of the door, and S any suitable locking means for securing the door in closed position.

From the foregoing description it will be observed that I have invented an improved construction of freight car door, particularly adapted for freight cars of the type having truss metal beams outside of the wooden inclosing sides, and in which the door will not only be securely supported and freely guided in its opening and closing

movements in a plane outside of the longitudinal plane of the truss beams, but in which a weather-proof joint will be maintained between the door supporting track and the supporting beam above the door opening so as to protect the interior of the car from the ingress of water through the opening between the top of the door and the car side.

What I claim is:

1. In a freight car, the combination with a side thereof having a door opening therethrough, of a sliding door closing said opening, a longitudinal metal beam extending along the upper edge of the car side and having a horizontal flange overlying the door opening, a track for supporting the door comprising a horizontal plate lapping and secured to the horizontal flange of said metal beam and a second horizontal plate underlying the horizontal flange of said metal beam and having a flange depending below said horizontal flange in a vertical plane intermediate of the outer edge thereof and the outer edge of said first plate, hangers secured to the top of the door each comprising an upper roller overlying and supported on said first horizontal plate and a lower guide underlying said first plate and lying adjacent the outer surface of said depending flange, and a longitudinal flange projecting upwardly from the inner edge of the door and overlapping the inner face of said depending flange.

2. In a freight car, the combination with a side thereof having a door opening therethrough, of a sliding door closing said opening, a longitudinal metal beam extending along the upper edge of the car side and having a horizontal flange overlying the door opening, a track for supporting the door comprising a horizontal plate underlying and secured to the horizontal flange of said metal beam and a second horizontal plate underlying said first horizontal plate and having a flange depending below said horizontal flange in a vertical plane intermediate of the outer edge thereof and the outer edge of said first plate, hangers secured to the top of the door each comprising an upper roller overlying and supported on said first horizontal plate and a lower guide underlying said first plate and lying adjacent the outer surface of said depending flange, and a longitudinal flange projecting upwardly from the inner edge of the door and overlapping the inner face of said depending flange.

3. In a freight car, the combination with a side thereof having a door opening therethrough, of a sliding door closing said opening, a longitudinal metal beam extending along the upper edge of the car side and having a horizontal flange overlying the door opening, a track for supporting the

door comprising a horizontal plate underlying and secured to the horizontal flange of said metal beam and a second horizontal plate underlying said first plate and integrally connected therewith at its inner edge, a flange depending from the outer edge of said second plate in a vertical plane intermediate of the outer edge thereof and the outer edge of said first plate, hangers secured to the top of the door each comprising an upper roller overlying and supported on said first horizontal plate and a lower

guide underlying said first plate and lying adjacent the outer surface of said depending flange, and a longitudinal flange projecting upwardly from the inner edge of the door and overlapping the inner face of said depending flange. 15

In testimony whereof, I have subscribed my name.

PERCY M. ELLIOTT.
